UNITED STATES PATENT OFFICE.

FRANK HUMPHRIS, OF PARKSTONE, ENGLAND, ASSIGNOR OF ONE-HALF TO KENNETH ALEXANDER ROBERTS, OF LONDON, ENGLAND.

MACHINE FOR MAKING TACKS, NAILS, RIVETS, PINS, OR THE LIKE.

Application filed December 12, 1922, Serial No. 606,496, and in Great Britain December 20, 1921.

The improved machine which is the subject of this invention comprises a number of forming dies which are mounted around the periphery of a rotatory cylindrical shell or drum and are split in planes passing through the axis of said drum, one part of each die being secured to the drum and the other part being movable radially by means of stationary cams carried by a cam shaft around which the drum rotates supported by extension pieces through which the cam shaft passes centrally, the cams acting through ejector rods to move the corresponding radially movable die parts to a closed position, to receive the material to be acted upon and to hold it whilst it is brought to the required shape in the dies, after which the movable die part is moved radially to eject the finished product. Around the drum are mounted means for cutting several wires or the like, for guiding and for thrusting them into the die cavities in which they are shaped as required by the operation of punch plates.

In these drawings:—

Figure 1 is an end elevation, of one type of a machine embodying the invention having some of the parts removed, and

Figure 2 is a front elevation of the machine partly in section through the dotted line A—A, as shown in Figure 1, with some of the parts removed.

Figure 3 is an end elevation on an enlarged scale partly in section, of the intermittently-rotating die-carrying cylindrical-shell and co-operating members.

Figure 4 is a perspective view partly in section of a part of the intermittently-rotating die-carrying-cylindrical-shell with a part of a radially-opening two-part-die.

Figure 5 is a perspective view, partly in section, of a multiple-head-forming pressure-punch-plate.

Like letters of reference refer to like parts throughout the drawings.

The framework *a* of the machine is arranged to accommodate a bolster *b*, ram *c*, an intermittently-rotating die-carrying-cylindrical-shell *d*, which is mounted in suitable bearings and a stationary-cam-shaft *e*. The die-carrying-cylindrical-shell *d* is provided with a number of two-part dies *f*, one part *f¹* of each is secured in the die-carrying-cylindrical-shell *d* and the other part *f²* is slidably-mounted therein so as to open and

close in a radial path; said two-part dies *f* are provided with a plurality of die-forming-cavities *f¹*, equally spaced and located with the axes thereof in alignment with the radially-placed joint or division *f²* existing between the engaging faces of the two-part dies *f*. One half or part *f⁴* of each said two-part die *f* is adjustably-secured in a transverse slot *d¹* by means of bolts *f³* or the like, within the periphery of said cylindrical-shell *d*; the other half or part *f⁵* of each said two-part die *f* is slidably housed or mounted in the remaining part of said transverse slot *d¹*. Connected to each of the said slidably-mounted half-die parts *f⁵* is a set of radially placed guide-stem-ejector-rods *g* provided with rollers *g¹* on their free ends; these ejector rods *g* pass through suitable radial perforations or bearings *d²* in the cylindrical-shell *d*, and engage through the medium of their rollers *g¹* at one period of the revolution of said cylindrical-shell *d* with a stationary ejector-cam *e¹*, they also contact for controlling their closing with an ejector-rod-return-cam *i* both located adjacent to the centre or axis of the cylindrical-shell *d*.

Attached to said die-carrying-cylindrical-shell *d* at one or both ends thereof, is provided a driven member or members *h* of an intermittent-gearing of the known kind, which is caused to move by its mating-part or parts *h¹*, suitably attached on the frame *a* of the machine and driven by bevel-gearing, shafts and the like *p* from its flywheel *j* in any known manner.

In combination with the said two-part dies *f*, and provided on the ram *c* of the machine is a multiple head-forming pressure-punch-plate *k* for finishing the products.

A transverse-thrust-bar *l* is constrained to move in a radial path and in alignment with the axis of the die-cavities *f¹* by means of director-rollers *u* attached to the copper-blade-ram *c¹* of the machine, which rollers *u* operate upon a set of director-levers *v* fulcrumed at one end thereof to a shaft *v¹* attached in suitable bearings to the frame *a* of the machine, and contacting at their other end with a set of rollers *l¹* provided on the transverse-thrust bar *l*. On extension-pieces *c²* secured to or integral with the copper-blade-ram *c¹* is provided a multiple-wire-copper-blade *o* which acts in combination with another blade *o¹* provided with cavities *o²* for guiding the stock or wire *m* into

the die cavities f^1 and this blade o^1 is secured to the frame a of the machine. The rod, wire or other stock m is fed into the machine by any suitable wire-feed mechanism, not shown in the drawings.

Diametrically opposite the heading or finishing-pressure-punch-plate k is an adjustable bolster b adjusted vertically by wedges g which are moved horizontally by bolts r .

10 The machine, the subject of this invention, will preferably be employed to feed and make into products a great quantity of rods or wires m side by side in multiple form, but for ease of description, it will 15 hereinafter be described as dealing with, and operating upon, one wire m and the process it goes through to manufacture a tack t .

The operations are as follows:—

A wire m is fed between the copper-blades o and o^1 and at the same time partly 20 into one of the multiple-die-cavities f^1 , and is cut off by the descending copper-blade o . As soon as the cutting-off operation is completed the intermittent-gears h and h^1 25 turn the cylindrical shell d around one division bringing the cut-off wire m^1 under the transverse-thrust-bar l which is constrained by its roller l^1 to force the cut-off wire m^1 deeply into the die f ; the intermittent-gear h and h^1 again comes into operation 30 and turns the cylindrical shell d round another division; bringing the cut-off wire m^1 under the finishing-punch-plate k by which it is headed and finished. The intermittent gear h and h^1 again comes into operation 35 and turns the cylindrical shell d round another division bringing the cut-off wire m^1 , now a finished tack t , away from under the heading plate k and into a non-operative position. The intermittent gear h and h^1 again comes into operation and turns the cylindrical shell d round another division and as this occurs the rollers g^1 on 40 the guide-stem-ejector-rods g ride up the cam face of the stationary-cam e^1 and force the slidably-mounted half f^5 of the two part die f out in a radial path, thus ejecting the finished tack t into a delivery chute s . The intermittent-gears h and h^1 again come into 45 operation and turn the cylindrical-shell d round another division; and whilst this is being done the rollers g^1 on the guide-stem-ejector-rods g on the sliding half f^5 of the die f are caused by the cam i to disengage 50 from the raised face of the cam e^1 and the sliding half f^5 of the die f is thus closed to its normal receiving position. These movements continue during the running of the machine.

55 The several heading, pointing and parting operations can be performed in this machine simultaneously by the several dies and on separate blanks, cut-offs or studs in quick succession, without putting undue strains on the die-carrying-cylindrical-shell-shaft, due

to the support of said cylindrical-shell by the bolster before referred to.

What I claim is:—

1. A machine for making tacks comprising a rotary cylindrical shell, a plurality of forming dies around the periphery of the shell, each of said dies being divided on a plane radial to the rotary shell to provide two members having oppositely arranged blank shaping cavities therein, one member fixed in the shell and the other movable radially therein, means for sliding the movable member outwardly radially with respect to the axis of the shell in contact with the fixed member, and means for retracting the said movable member. 75

2. A machine for making tacks comprising a rotary cylindrical shell, a die member fixed in the shell, a die member movable radially with respect to the axis of the shell, the said dies being arranged in contact and having oppositely arranged cavities forming a single blank shaping die cavity and stationary cams arranged within the shell to effect the positive sliding movement of the said movable die member radially in contact with the fixed member in opposite directions respectively. 85

3. A machine for making tacks comprising a rotary cylindrical shell, a plurality of movable die members respectively coacting with corresponding fixed die members, the said die members being arranged in pairs in contact on a plane radial to the rotary shell and each having parts of a single blank shaping cavity formed therein, and means for sliding said movable die members radially with respect to the axis of the shell in contact with the fixed members. 95

4. A machine for making tacks comprising a rotary cylindrical shell, a plurality of die members fixed in the shell, a plurality of movable die members respectively coacting with the fixed die members and in sliding contact therewith on planes radial to the rotary shell, said opposing die members having complementary oppositely arranged die cavities in each of the pairs consisting of a fixed and a movable die member, and means for positively sliding the said movable die members separately in contact with the fixed members in a direction radial to the axis of the shell. 100

5. A machine for making tacks comprising a rotary cylindrical shell, a plurality of die members arranged in pairs, each pair comprising one member fixed in the shell, and a die member movable radially in the shell in contact with the fixed member, the contacting faces of the members being respectively arranged radially to the axis of the shell, the contacting faces having oppositely arranged complementary blank receiving cavities, and means for sliding the movable die members separately in their radial direction. 110

of movement in contact with the fixed members.

6. A machine for making tacks comprising a rotary cylindrical shell, a plurality of die members arranged in pairs spaced apart around the shell, each pair comprising a member fixed in the shell, and a die member movable radially in the shell in contact with the fixed member on a plane radial to the shell, the contacting members having oppositely arranged complementary cavities forming a single blank shaping cavity, means for imparting an intermittent rotary motion to the shell, means for holding the movable members stationary with respect to the fixed members as each pair of members is moved through a predetermined arc, means for separately sliding said movable members outwardly in a radial direction with respect to the axis of the shell in contact with the fixed members, and means for retracting said movable members.

7. A machine for making tacks comprising a rotary cylindrical shell, a plurality of die members fixed in the shell, a plurality of die members movable in the shell in contact with the fixed die members on a plane radial to the rotary shell, each die member having a part of a single blank shaping die cavity formed therein, a finishing punch, means for intermittently rotating the shell to bring pairs of die members in succession beneath the said punch, and means for separately sliding said movable die members radially with respect to the axis of the shell in contact with the fixed die members.

8. A machine for making tacks comprising a rotary cylindrical shell, a plurality of die members fixed in the shell, slots in the shell, a plurality of die members movable in the shell, the said members being arranged in pairs in contact on planes radial to the rotary shell and each member of a pair having part of a blank forming cavity complementary to the cavity of the other member, a thrust bar, means for intermittently rotating the shell to bring pairs of die members in succession into alignment with the thrust bar, and means for separately sliding said movable die members radially with respect to the axis of the shell in contact with the fixed die members.

9. A machine for making tacks comprising

ing a rotary cylindrical shell, die members arranged in pairs in contact on a plane 55 radial to the rotary shell and having oppositely disposed blank shaping cavities therein, one member of each pair being fixed in the shell and the other movable therein, a finishing punch movable radially with respect to the axis of the shell, a bolster arranged diametrically opposite to the finishing punch and means for separately moving said movable die members radially with respect to the axis of the shell. 60 65

10. A machine for making tacks comprising a rotary cylindrical shell, die members arranged in pairs one member of each pair being fixed and the other movable in a slot in the shell, means for bringing the members of each pair into register, die cavities enclosed between the members of each pair, means for feeding material into the die cavities, means for cutting off to the required length the material fed into the die 70 75 cavities, and means for imparting a sliding movement to the movable die members in a direction radial to the axis of the shell.

11. A machine for making tacks, comprising a rotary cylindrical shell having a radial 80 slot, a die member fixed in the shell, a die member in contact with the fixed member and movable radially with respect to the axis of the shell in said slot, and means for positively sliding the said movable die member 85 in both directions in contact with the fixed die member.

12. A machine for making tacks, comprising a rotary cylindrical shell having a 90 radial slot, a die member fixed in the shell, a die member in contact with the fixed die member and slidale radially with respect to the axis of the shell in said slot, said die members having oppositely arranged blank shaping cavities in the contacting faces, means 95 for bringing the slidale member in contact with the fixed die member to a position in which the blank shaping cavities are in positions to hold a blank therein, and means for moving the slidale die member radially 100 to the shell to eject a finished blank from between the said die members in contact with the fixed die member.

London, England, 1st December, 1922.

FRANK HUMPHRIS.
